PISTON EXPANDING MEANS

Filed Oct. 25, 1926

FIG. 4 *INVENTOR.*
FREDERICK E. G.

FREDERICK E COWLE

BY A.B. Bowman

ATTORNEY

UNITED STATES PATENT OFFICE

FREDERICK E. COWLE, OF SAN DIEGO, CALIFORNIA, ASSIGNOR OF ONE-THIRD TO DAVE S. BONE AND ONE-THIRD TO JOHN W. COOLEY, BOTH OF SAN DIEGO, CALIFORNIA

PISTON-EXPANDING MEANS

Application filed October 25, 1926. Serial No. 144,095.

My invention relates to a piston expanding means; and the objects of my invention are: first, to provide a tool for forcibly and permanently increasing the diameter of a piston or other cylindrical body; second, to provide a tool in which the expanding force is exerted radially, equally and evenly throughout the length of the cylindrical body undergoing expansion; third, to provide a tool of the class described which may be inserted within a hollow cylindrical body, having bosses or similar protuberances on its inner surface.

With these and other objects in view, as will appear hereinafter, my invention consists of certain novel features of construction, combination and arrangement of parts, as will be hereinafter described in detail and particularly set forth in the appended claims, reference being had to the accompanying drawings and 20 to the characters of reference thereon, which form a part of this application, in which:

Figure 1 is a front elevational view of the device, partly in section and showing the device applied to a piston, shown in dotted lines; Fig. 2 is a plan view in section through the line 2—2 in Fig. 1; Fig. 3 is a side elevational view of the device, the expansion screw being shown in part only, and Fig. 4 is a plan view in which the expansion screw and two of the 30 cover plate screws are shown in section.

Like reference characters refer to similar parts and portions throughout the several views of the drawings.

The principal parts of my piston expanding device are the tapered core member 1, the several annular, segmental dies or quarter sections 2, 3, 4 and 5, the expansion screw 6, cover plate 7 and cover plate screws 8, 9, 10 and 11. These parts I prefer to make of steel.

The tapered core member 1 is in form a frustum of right circular cone, and is bored through axially and provided with internal screw threads 1^a. The sections 2, 3, 4 and 5 form together substantially a hollow cylindrical die, as shown in Fig. 2, their outer surfaces forming a cylinder when the sections are grouped together, while the inner surfaces form an axially extending, tapered, circular opening corresponding to the taper of the core member 1. The lower ends of the sec-

tions are cut away in part, forming a rectangular channel extending transversely across the bottom end of the die and axially approximately two-thirds the length of the die, the side surfaces limiting this channel being represented by the quarter section surfaces 2^a, 3^a, 4^a and 5^a and the upper surfaces 2^b, 3^b, 4^b and 5^b, as shown in Figs. 2 and 3. As clearly illustrated in Fig. 1, the object of this channel is to provide clearance for the bosses 12^a and 12^b in the piston 12, shown in dotted lines. The upper ends of the several quarter sections form an annular, axially extending rim, with inner surfaces 2^c, 3^c, 4^c and 5^c, which serve to embrace the outer cylindrical surface 55 of the cover plate 7.

The expansion screw member 6 comprises a bar having a lower threaded portion 6^a suitable for screwing into the core member 1, an unthreaded upper portion 6^b, provided with 60 a removable crossbar 13 at the top end, for enabling the exertion of considerable manual force on the screw member 6, and a narrow annular collar 6^c, preferably forming an integral part of the said bar, located between 70 the threaded and unthreaded portions thereof.

The cover plate 7 is a strong circular plate provided with a centrally located, circular opening, said opening being counterbored to a 75 depth of about half the thickness of the plate to a diameter somewhat greater than that of the collar 6^c, and forming within the plate 7 an annular seating 7^a against which the upper surface of said collar rests, while the bar 80 portion 6^b of the expansion screw 6 is free to pass through the opening. The crossbar 13 is, of course, removed until the parts are assembled. The cover plate 7 is provided with a plurality of radially elongated slots 13, 14, 85 15 and 16 through which the bolts 8, 9, 10 and 11 are free to pass, said bolts being screwed into suitably threaded holes, not shown, in the quarter sections 2, 3, 4 and 5. The bolts 8, 9, 10 and 11 are so positioned when the quarter 90 sections are grouped to form a complete cylinder that they occupy the inner ends of the slots 13 and 14, while the cover plate 7 is registered by the annular rim formed by the surfaces 2^c, 3^c, 4^c and 5^c of the quarter sections. 100

In Fig. 1 the device is shown in its assembled form, placed within the piston 12. The latter is shown with surface grooves or splits 12^a, which it is customary to provide in pistons for facilitating expansion and contraction due to heating during normal operation. The core 1 is shown in a position close to the cover plate 7. In this position the dies 2, 3, 4 and 5 are an easy fit within the piston, 5 the wrist pin bosses 12^a and 12^b of the latter occupying the rectangular channel as previously explained. By revolving the expansion screw 6, the core 1 may be forced downwardly within the dies 2, 3, 4 and 5, forcing them 10 outwardly. The upward thrust on the expansion screw 6 is taken by the collar 6^c and the annular seating 7^a in the cover plate 7. It will be understood that, due to the very great leverage obtained by this construction, 15 a considerable radial expanding force may be exerted upon the inner surfaces of the piston. The radial outward movement of the dies 2, 3, 4 and 5, in consequence of the downward movement of the core 1, causes the screws 8, 9, 10 and 11 to be displaced outwardly, the elongated slots 13^a, 14, 15 and 16 20 in the cover plate 7, through which they pass, permitting this displacement.

In applying the expansion means herein 25 described in the process of expanding pistons of aluminum alloy, I distinguish between pistons having the surface splits and those without such splits. In the case of pistons having surface splits, I first insert the tool, as previously described, bringing the dies into easy 30 pressing fit with the interior piston surface. I then heat the piston and tool to a temperature of from 400 to 800 degrees Fahrenheit. While at this temperature, I expand the piston 35 by means of the expansion tool. At this temperature I have found that the metal takes on a permanent set, so that after allowing the piston to cool somewhat and removing the tool, the outer diameter of the piston 40 will have increased considerably. It is then possible to refinish the outer surface to a greater diameter than that of the untreated piston.

In the case of pistons having no splits in 45 their outer surface, I prefer to first split the piston similarly to the conventional split surface piston, then proceed in the manner as above set forth.

It is clear that in the process I have 50 described, I bring about the permanent expansion of the piston by bringing the temperature of the metal to a critical value at which the inherent elasticity is greatly reduced. By subjecting the walls of the piston 55 to relatively great radial pressure, evenly distributed over their surface, I am able to increase the peripheries of the said walls; that is, the diameter of the piston which occurs while the metal is still at the above 60 mentioned critical temperature. Thus, when

the metal is allowed to cool while restrained by means of the expansion tool, it does not again contract. The process, however, does not permanently affect the inherent qualities of the metal, since once it has been allowed 70 to cool down, said qualities are substantially restored to those existing previously to the treatment.

Though I have shown and described a particular construction of device and a certain process used in conjunction with said device, 75 I do not wish to be limited to this particular construction and process, but desire to include in the scope of my invention the construction substantially as set forth in the so appended claims.

Having thus described my invention, what I claim as new and desire to secure by Letters Patent is:

1. In a device of the class described, a 85 hollow, internally threaded tapered core member, a plurality of annular segmental dies forming together a substantially cylindrical outer surface and an axially extending tapered opening capable of receiving said core member in intimate surface contact and forming also a transverse, axially extending channel, rotatably screwably mounted means 90 adapted to fit in said hollow, internally threaded portion of said core member for forcing said core member axially with respect to the said dies, and further means for restraining said longitudinal forcing means from other than rotary movement. 95

2. In a device of the class described, a 100 tapered core member, a plurality of annular segmental dies, their outer surfaces forming together a substantially cylindrical surface, their inner surfaces forming a tapered, 105 axially extending opening capable of receiving said core member in intimate surface contact and forming also a transverse channel permitting passage of said dies over protuberances extending within the confines of said cylindrical outer surface, and means 110 for forcibly moving said core member in an axial direction within said segmental dies. 115

3. In a device of the class described, a 120 tapered core member having a threaded, axially extending hole throughout its length, a threaded expansion bar capable of screwing into said core, a plurality of annular segmental members forming a substantially cylindrical outer surface and a tapered inner, 125 axially extending opening, capable of receiving said core member in intimate surface contact, a circular cover plate to which said annular segmental members are radially movably secured, said cover plate having a central opening through which the expansion bar is free to pass, and a collar integral with said expansion bar located between the upper core member surface and lower cover plate surface. 130

4. In a device of the class described, a 130

hollow, internally threaded, tapered core member, a plurality of annular segmental dies, their outer surfaces forming together a substantially cylindrical surface, their inner surfaces forming a tapered axially extending opening capable of receiving said core member in intimate surface contact and forming also a transverse channel permitting passage of said dies over protuberances
5 extending within the confine of said cylindrical outer surface, an externally threaded expansion bar screwably mounted within said hollow, internally threaded, tapered core member, and means for holding said expansion bar in rotatable and non-slidable relation to said segmental dies.

In testimony whereof, I have hereunto set my hand at San Diego, California, this 8th day of October, 1926.

20 FREDERICK E. COWLE.
